UNITED STATES PATENT OFFICE.

FRANK PHELPS, OF LITTLE ROCK, ARKANSAS.

COTTON-GIN.

1,013,053.

Specification of Letters Patent. Patented Dec. 26, 1911.

Application filed July 8, 1910. Serial No. 571,081.

To all whom it may concern:

Be it known that I, FRANK PHELPS, a citizen of the United States, residing at Little Rock, in the county of Pulaski and State of Arkansas, have invented certain new and useful Improvements in Cotton-Gins, of which the following is a specification.

The object of my invention is to improve the construction and operation and increase the efficiency of gins in which the lint is stripped from the saws by an air blast.

Previous to my invention, air blast gins were constructed with a longitudinal blast-pipe taking in the air at one end of the gin and discharging it laterally through the usual elongated blast-nozzle adjacent to the saws or gin-cylinder. The air rushing through the pipe caused an uneven pressure at the nozzle, the pressure increasing toward the end of the gin farthest from the air inlet or receiving-end of the pipe. This condition was only partially relieved by the use of baffle-wings or other obstructions in the air pipe.

Another and more serious difficulty was that eddy currents would occur at the mouth or in the intake end of the lint off-take flue, tending to back up the lint which would be again picked up by the saws and deposited in the lower ends of the ribs. This is what is commonly known as "back-lash," which has always been the cause of a great deal of trouble and danger, not only from injury to the machinery, but also because of the liability to start fires.

The above-mentioned difficulties are overcome by my present invention, which produces an even pressure along the entire length of the blast nozzle, and prevents the formation of the said objectionable and dangerous eddies in the mouth or throat of the lint flue; besides which my invention produces a very efficient stripping blast with the use of a fan or blower of smaller capacity than commonly required in gins of the character under discussion.

In the accompanying drawing, which forms a part of this specification: Figure 1 shows a gin embodying my invention in vertical cross section; Fig. 2 is an enlarged view of the air blast stripping portion of the gin.

The gin selected for illustrating the invention embodies in its construction the mot-
55 ing or cleaning adjustment of my prior patent, No. 809,131, dated Jan. 2, 1906.

My invention will be hereinafter described with reference to said drawing, and then particularly pointed out in the appended claims.

In the drawing, 1 is the roll-box, 2 the gin-cylinder or saws, and 3 the breast or ribs.

4 is the moting chamber, 5 the divider board, and 6 the screw-conveyer of the cleaning attachment substantially as set forth in my prior Patent No. 809,131; the back portions of the saws being exposed in said chamber to permit ejection by centrifugal force of motes, dust and other foreign particles which settle in the trough-like bottom of the chamber and are removed by the screw-conveyer.

Behind the gin-cylinder is an air-reservoir 7, which is or may be a box-like compartment of large capacity, extending the full length of the gin-cylinder. It has preferably in the back wall thereof an opening 8 for connection with the supply pipe through which the air is forced into the reservoir from the fan or other suitable type of blower (not shown). In a battery comprising a plurality of gin stands, the air is or may be conveyed through a main pipe, indicated at 9, running back of the several gins and having separate branch pipes, one of which is shown at 10, connected with the respective openings 8 of the several gins.

The air-reservoir is contracted at its front, as indicated at 11, and terminates adjacent the gin-cylinder with an elongated slot-like nozzle 12 for emitting the stripping blast against the peripheral portions of the saws in the general direction of rotation thereof and approximately at a tangent. The blast-nozzle 12 is restricted as compared with the air inlet opening 8; thus in a battery of four seventy-saw gin-stands, where the air-reservoir of each gin is supplied by a separate pipe, the aggregate area of the four blast-nozzles is preferably equal to the area of one four-inch pipe, it being understood that I do not intend to restrict myself to this or any particular proportions, however. With this arrangement, the air has no tendency to rush through the air-chamber or reservoir as the openings are so small and the air-reservoir so large that the latter simply becomes inflated. Thus the air-reservoir 7 is charged or stored with compressed air forced thereinto by the blower, and, the air being delivered into this storage chamber

at the center of the gin, instead of flowing through the gin from end to end, there is produced at all times an even pressure along the entire length of the blast-nozzle, over-
5 coming what has been a difficult problem of previous constructions of air blast gins, in which, as aforesaid, it has been necessary to use deflectors or obstructions in the air-pipes to alleviate the uneven pressure at
10 the blast nozzle.

To control the blast and avoid back-lash by preventing the formation of eddies at the mouth or in the throat of the lint-flue, I provide what may be termed a "wind-
15 board" 13, having a wide smooth surface over which the blast is blown. The said surface of the wind-board, which is preferably convex or curved, extends from the lower lip of the blast-nozzle close to the saws and
20 then beyond and away from the saws, the lower part of the wind-board being considerably below the blast nozzle. It is an established fact that a thin current of air projected over a smooth surface will follow
25 the said surface, since the current tends to create a vacuum or suction between it and the said surface and is thus subjected to unequal atmospheric pressures. Utilizing this principle in my invention, it will be
30 seen that the blast following or blowing over the smooth convex surface of the wind-board will blow the lint directly off the saw teeth and then downwardly and outwardly therefrom. The wind-board may be
35 a wooden panel, or a metal plate, or other suitable member.

The wind-board extends well down into and forms the back wall of the throat 14 of the lint-flue 15, which extends rearward of the air-reservoir. The other wall of
40 the throat 14 is formed by a curved extension 16 of the bottom wall of the lint-flue, which extension 16 passes under the lower edge of the wind-board, then upward in
45 front of the lower portion of the wind-board and terminates with a lip adjacent the gin-cylinder, so that a segment of the surface of the gin-cylinder is substantially inclosed between the upper lip of the blast-
50 nozzle and the lower lip of the throat of the lint-flue. The wind-board also extends beyond or below the top wall of the lint-flue, which, in the preferred construction illustrating my invention, is separated from
55 the air-reservoir by a common partition wall. Hence the narrow throat 14 opens into an enlarged space at 17 immediately back of the wind-board, relieving the air current as soon as it passes under the lower
60 edge of the wind-board. This sudden relief of the air current allows the eddy to occur just back of the lower edge of the wind-board, and prevents the formation of eddies in the throat of the lint-flue, so that the lint
65 stripped by the blast from the saws passes

down through the narrow throat of the lint-flue in a direct and practically straight line, and the danger of back-lash is thereby obviated.

By restricting the blast-nozzle and having a direct line for the stripping blast across the peripheries of the saws, without short curves, and having a large air-chamber in which the air is stored between the inlet and the blast-nozzle, I am enabled to use a much smaller fan and produce a much heavier pressure and also handle a considerably smaller volume of air, which, in itself, is a very great advantage, as it reduces the power at least fifty per cent., as compared with previous constructions of air blast gins, also enabling me to use a single thirty inch drum in the condenser carrying four seventy-saw gins with safety, as against a double thirty inch drum or single sixty inch drum as required in previous constructions.

My invention may be embodied in other forms, and hence I do not desire to restrict myself to that shown.

I claim as my invention and desire to secure by Letters Patent:

1. In a gin having an air blast stripper, the combination with the gin-cylinder and blast nozzle for emitting the stripping blast against the peripheral portions of the saws, of a wind-board adjacent the gin-cylinder having a wide smooth surface over which the stripping blast blows, and a lint offtake flue, the said surface of the wind-board forming one wall of the throat of said flue.

2. In a gin having an air blast stripper, the combination with the gin-cylinder and blast nozzle for emitting the stripping blast against the peripheral portions of the saws, of a wind-board adjacent the gin-cylinder having a wide smooth surface over which the stripping blast blows, and a lint offtake flue having a narrow throat, one wall of which is provided by the wind-board, the lint flue being enlarged immediately back of the wind-board.

3. In a gin having an air blast stripper, the combination with the saws, of an air-chamber back of the saws having a blast-nozzle for emitting a stripping blast, a rearwardly extending lint-flue under said air-chamber, a wind-board arranged adjacent the saws under the blast nozzle and having a smooth surface over which the blast is projected, said wind-board extending below the upper wall of the lint-flue, the lower wall of the lint-flue having a curved extension confronting said surface of the wind-board and in conjunction therewith providing a narrow throat to the lint-flue.

4. In a gin having an air blast stripper, the combination with the saws, of a lint offtake flue, an air-chamber having a blast-nozzle for emitting a stripping blast against the peripheral portions of the saws and into

the throat of the lint flue, and a wind-board adjacent the saws having a smooth convex surface extending from the lower lip of the blast-nozzle into the throat of the lint flue and forming one wall of the latter.

5. In an air-blast gin, the combination with the gin-cylinder, of an air-reservoir having a blast-nozzle for emitting a stripping blast, means for forcing air into the 10 air-reservoir at the middle portion thereof, a lint-flue having a throat into which the blast discharges, and means for guiding the blast across the saw-perimeters in a direct line from the blast nozzle into the throat of the 15 lint-flue, the lint-flue being enlarged back of the base of the lint throat to suddenly relieve the current and prevent eddies in the throat of the lint-flue.

6. In an air blast gin, the combination 20 with the gin-cylinder, of an air-chamber having a blast-nozzle and a wind-board having a wide smooth surface extending close to the gin-cylinder and beyond and away therefrom, the blast-nozzle being arranged 25 for directing the blast over said surface, whereby the blast blows the lint directly off and away from the saw teeth.

7. In an air blast gin, the combination with the gin-cylinder, of an air-chamber having a nozzle arranged for emitting a stripping blast against the peripheral portions of the saws, and a wind-board having a smooth convex surface extending from the lower lip of the blast-nozzle close to and beyond the portion of the gin-cylinder from 35 which the lint is stripped.

8. In an air blast gin, the combination with the gin-cylinder, of an air-chamber having a blast-nozzle arranged for emitting a stripping blast, a wind-board adjacent 40 the gin-cylinder having a wide smooth surface over which the blast is directed, and a lint flue the throat of which is formed in part by the said surface of the wind-board, there being a space back of the wind-board 45 in communication with the throat of the lint-flue whereby the current is relieved and eddies are prevented in said throat.

In testimony whereof I affix my signature, in presence of two witnesses.

FRANK PHELPS.
